UNITED STATES PATENT OFFICE.

HUZEWO TAKATA, OF TOKYO, JAPAN.

SAFETY LAMP FOR MINES.

Application filed September 15, 1925. Serial No. 56,447.

The principal object of the present invention is to provide a safety lamp with which the amount of those gases contained in the air in mines which are liable to an explosion can be easily measured. At present, gas measuring lamps are used for the purpose of measuring gases and ordinary lamps serve for the lightening only. As it is difficult to use these measuring lamps from place to place, in mines, miners are unaware even of the nearest approach of danger. But if the safety lamps of this invention are used in place of ordinary lamps, gases can easily be measured whenever and wherever necessary, and consequently the danger of explosion can be avoided.

Further, safety lamps of this invention are so constructed as to facilitate an accurate measurement of gases.

Another object of this invention is to provide a safety lamp, in which the fire is extinguished, before the lamp chimney is removed, and therefore the fire is in no case exposed to the air.

According to the present invention, therefore, a cap is provided to secure a wick holder at a center part of lamp, and on the said cap stand vertically indicating needles or pins, by means of which the height of flame is measured. A rest or support for a lamp chimney is adapted to be screwed with the cap, and while releasing from an oil pot, brings the cap upward with it, and put out the fire.

The invention will now be described more completely with reference to the accompanying drawings in which:

Fig. 1 is a partly sectional elevation of a safety lamp according to the present invention, and

Fig. 2 is a sectional plan view of the same.

In these drawings, (a) represents a hollow dome-shaped cap, forming a cylindrical block at its center part, which is provided with a hole (c), piercing vertically through the block. A wick is held in the wick holder (b) which is adapted to fit closely to the hole (c) and slides upwards and downwards therethrough. Several indicating pins (d) of different length are fixed to the upper surface of the cap (a) and stand vertically on it and around the hole (c).

The lowermost part of the outside periphery of the cap (a) is threaded as at (e), and its inner lowermost circumference is formed into an annular flange (g), pro-

vided with recesses or void spaces (h) and (i), for the fastenings (k) and (j) respectively, fixed to the upper surface of the oil pot (m). The fastening (j) is adapted to 60 pass through the recess (i), and the fastening (k) through the recess (h).

The support or rest (o) for the lamp chimney (g) is fastened to a ring or short cylinder (p), by passing outwardly projecting pins fixed on the outer surface of the support (o) through the void places on the inner surface of the ring (p), and partly rotating the support (o) until the above pins are arrested by the pins standing on 70 the upper surface of the ring (p). Thus the support (o) is kept on the ring against the action of the spring pressing the lamp chimney downward. The support (o) is adapted to be connected also with the cap 75 (a) by means of the threads (e) of the cap (a) and the nut (e') formed on the inner surface of the cylindrical boss of the support (o).

The cap (a) is connected or disconnected with the oil pot (m) by passing the fastenings (j) and (k) through the void spaces (i) and (h) on the flange (g) respectively.

To connect the support (o) with the cap (a) is as follows:—The support (o) for the lamp chimney is first fastened to the ring (p), and the cap (a) to the oil pot (m). Then the oil pot (m) is connected with the ring (p) by means of the screw (m') by their relative rotation, the threads (e) of the cap (a) being fastened to the support (o) at the same time. Thus the cap (a) is connected with the support (o) and is pressed by it against the oil pot (m) as shown in the Figures (1) and (2).

With these constructions, when the oil pot (m) is released from the ring (p), the cap (a) remains fastened to the support (o), and therefore the wick holder (b) is lowered relatively to the cap (a), and the fire extinguished. Thus the fire is in no case exposed to the air.

The flange (g) of the cap (a) is provided with two void spaces other than the void spaces (h) and (i). They are formed smaller than (h) and (i), and serve to fasten the cap (a) to the oil pot (m) by engaging with the projection (n) of the fastening (k) when the oil pot (m) is withdrawn from the ring (p), and, therefore, 110 the cap (a) is withdrawn together with the oil pot (m).

The wick holder (*b*) is moved upwards and downwards by means of a screw bolt (*r*).

The principal advantage of this invention 5 is that the amount of gases in mines can be measured without using measuring lamp. For this purpose, the wick holder (*b*) is lowered slowly until combustion of oil sucked up by the wick becomes minimum, 10 and the gases entering into the lamp chimney burns on the holes (*c*). The height of flame, judged by comparing with those of indicating pins (*d*) indicates the percentage of gases contained in the air. In measuring lamps, now in use, indicating scales are 15 fairly apart from flame, and therefore, it is unable to know the amount of gases accurately, this being effected in a safety lamp according to the present invention, in which 20 the indicating needles stand close to flame to be observed.

What I claim as new is:

1. A safety lamp of the character described including, in combination, an oil pot 25 or reservoir, a chimney, means detachably connected to said oil pot or reservoir for supporting said chimney, a hollow dome-shaped cap adapted to be connected to said supporting means and also having a connection with said pot or reservoir, said last- 30 mentioned connection permitting limited relative movement between the parts when released, said cap having a bored projection to receive a wick, and a plurality of indicating pins extending vertically upwardly from the outer surface of said cap adjacent said bored projection whereby the height of flame due to the combustion of explosive 35 gases can be measured by comparison.
2. A safety lamp of the character described including, in combination, an oil pot 40 or reservoir, a chimney, a supporting means for said chimney, a ring or annular member to which said supporting means is adapted 45 to be connected, said supporting means also

being adapted to be connected to said oil pot or reservoir, a hollow dome-shaped cap provided with a centrally located and bored projection, a wick holder connected to said pot or reservoir and slidably in said bored projection, said cap being connected to said supporting means, and means connecting said pot or reservoir and said cap but permitting a limited relative movement between them whereby when said pot or reservoir is released and withdrawn, the wick holder will be drawn down into said bored projection to extinguish the flame. 55

3. A safety lamp of the character described including, in combination, an oil pot 60 or reservoir, a chimney, means for supporting said chimney adapted to be detachably connected to said oil pot or reservoir, a hollow dome-shaped cap member provided with a centrally located bored projection and 65 adapted to be connected to said supporting means, a wick holder connected to said pot or reservoir and slidably in said bored projection and means connecting said pot or reservoir and said cap but permitting a limited 70 relative movement between them.

4. A safety lamp of the character described including, in combination, an oil pot 75 or reservoir, a chimney, means for supporting said chimney adapted to be detachably connected to said oil pot or reservoir, a hollow dome-shaped cap member provided with a centrally located bored projection and adapted to be connected to said supporting means, a wick holder connected to said pot or reservoir and slidably in said bored projection and means connecting said pot or reservoir and said cap but permitting a limited relative movement between them, 80 said means including a flange on said cap and engaging members connected to said pot or reservoir. 85

In testimony whereof, I have signed my name to this specification.

HUZEWO TAKATA. [L. s.]
